Original application August 7, 1935, Serial No.
 35,022. Divided and this application January
 11, 1936, Serial No. 58,826

4 Claims. (Cl. 74—396)

This invention relates to internal combustion motors and particularly to fuel induction systems therefor. More particularly it relates to a specific form of supercharger construction particularly adaptable for commercial use with internal combustion motors.

This application is a division of applicant's prior co-pending application, Serial No. 35,022, filed August 7, 1935, in which the structure shown herein is shown and described and further the specific manner in which the supercharger structure is mounted upon an internal combustion engine is claimed. While applicant's prior co-pending application referred to above is primarily directed to a novel mounting of a supercharger on an internal combustion engine, the present application has for a general object the provision of a novel gear drive for supercharger structure and novel means for mounting the gearing in the housing of the supercharger and with respect to the motor.

Other objects of the invention include the provision of a supercharging construction for internal combustion motors including a rotatable impeller driven through a worm and wheel, the worm and wheel being so constructed and arranged with respect to the impeller that the axial force imparted to the worm because of its driving relation with respect to the wheel is offset in part or in whole by the pneumatic forces acting on the impeller, thereby relieving the bearings for the impeller drive shaft from the load they might otherwise be subjected to.

Further objects of the invention include the provision of a novel supercharger construction having novel means for maintaining the proper driving relation between the driving worm and the wheel thereof; the provision of a supercharger including a worm and wheel and in which a sub-assembly is provided including a removal cover element provided with a bearing assembly for the worm wheel shaft and so cooperating therewith as to limit the axial position thereof and which is applicable to and removable from the supercharger as a unit; and the provision of a supercharger construction including a worm and wheel assembly of the area contact type, together with a bearing arrangement therefor permitting ready assembly and disassembly of the worm wheel with respect to the worm.

Still further the present invention contemplates the provision of a drive mechanism for supercharger construction, in which novel means are provided for interconnecting the gear drive shaft of the supercharger proper with the ac-

cessory shaft of the internal combustion engine with which the supercharger is associated.

The above being among the objects of the present invention, the same consists in certain novel features of construction and combination of parts to be hereinafter described with reference to the accompanying drawings, and then claimed, having the above and other objects in view.

An illustrative embodiment of the invention is shown in the accompanying drawings, in which:

Fig. 1 is a view in side elevation of a conventional in-line type of internal combustion motor equipped with my improved supercharger, the lower portion of the motor being broken away.

Fig. 2 is a diagrammatic view in front elevation of the same illustrating the manner in which the accessory shaft is driven in conjunction with the cam shaft from the crank shaft of the motor.

Fig. 3 is an enlarged fragmentary top plan view of the supercharger mounted on the motor but with the carburetor removed from the top of the supercharger.

Fig. 4 is a transverse vertical sectional view taken on the line 4—4 of Fig. 3, showing the motor, intake manifold, and supercharger.

Fig. 5 is an enlarged sectional view of the supercharger taken on the line 5—5 of Fig. 4, and with a portion of the gear case housing broken away to show the interior thereof.

Fig. 6 is an enlarged fragmentary sectional view taken on the line 6—6 of Fig. 5, showing in detail the manner in which the lower end of the impeller shaft is mounted in the supercharger housing.

Fig. 7 is an enlarged sectional view taken substantially on the line 7—7 of Fig. 4, showing in detail the mounting of the worm wheel and its connection to the accessory shaft.

Fig. 8 is a sectional view taken substantially on the line 8—8 of Fig. 7, illustrating in further detail the mounting of the worm wheel on its shaft within the supercharger housing.

Fig. 9 is a sectional view taken substantially on the line 9—9 of Fig. 5, showing the manner in which the worm wheel and its shaft is assembled with respect to the worm which it serves to drive and the manner of mounting this worm wheel within the supercharger housing.

In the construction shown in the drawings, a conventional type of cylinder in-line internal combustion motor 20 is shown provided with the improved supercharger generally designated at 21 mounted on the crank case thereof and driven by an accessory shaft 22 which also drives

water pump 23 and generator 24. The generator 24 is attached to that side of the supercharger driving gear housing opposite to the supercharger's attachment to the accessory shaft 22 so that the generator is in reality driven by the drive shaft of the supercharger which in turn is actuated by the accessory shaft as shown more clearly in Fig. 7.

The supercharger, per se, comprises a generally vertically disposed housing, the middle portion 25 of which will be hereafter designated as the impeller shaft housing; the lower portion 26, which will be hereafter referred to as the driving gear housing, and the upper part 27, which will be hereafter referred to as the lower half of the impeller housing. A complementary cover plate or housing 28 is secured to the housing 27 by bolts and cap screws 29 so as to form a suitable enclosure for the impeller of the supercharger.

Means are provided for driving the supercharger and comprise a flexible coupling 41, one end of which is attached to the accessory shaft 22, and the other end of which is provided with an interiorly splined hub 42 which telescopes on the complementary splined end 43 of a driving gear shaft 44. A nut 45 is threaded on the reduced threaded end of the shaft and bears against a washer 46 and which in turn abuts against the splined hub 42. The driving gear shaft 44 is provided with an integrally formed radially extending hub 47 medially of its ends to which is secured a drive gear 48 of the cone type by means of a series of cap screws 49.

The end of the shaft 44 opposite to that connected to the accessory shaft is journaled in a removable bushing 50 which is mounted in the depressed end wall 51 of the driving gear housing 26, and the other end of the shaft at the opposite side of the hub 47 is journaled in a bearing 52 mounted in the cover plate 30. A thrust bearing 53 is provided between the inner radially flanged end of the bearing 52 and the hub 47, its location on the shaft being accurately positioned by a series of shims 54, the shims being supplied in variable thicknesses. Pins 55 are fixed in the thrust bearing 53 and extend axially of the shaft with their ends fitting in apertures provided in the hub 47 so that the thrust bearing is constrained to rotate with the hub. A bearing washer 56 is secured by pins 57 to the outside of the cover plate 30 and forms one-half of a second thrust bearing, the other half of which comprises a ring or washer 58 which is clamped against a series of variable thickness shims 59 by a reduced inner end 60 of the hub 42.

The outer surface of the hub portion 60 is accurately turned and smoothed so as to be adaptable for having an oil seal 61 bear thereon, the oil seal being carried by a supplementary cover plate 62. With this arrangement opposite sides of the cover plate are impressed by the thrust bearings and the driving gear 48 is accurately positioned within the housing 26 by the location of the driving gear shaft 44 in its cover plate bearing.

The bearing 50 which is held in position by screws 63, when removed as shown in Fig. 9, permits a tilting or tipping of the driving gear shaft 44 with its gear 48 assembled thereon and secured in adjusted position in the cover plate bearing so that the driving gear 48 may be assembled radially with respect to its driven worm 64 inasmuch as it is impossible to mesh and unmash gears of the cone surface contact type by side-wise movement, as viewed in this figure.

The worm 64 is splined on the lower end of a vertically disposed impeller shaft 65 which is journaled immediately above and below the worm in the bearings 66 and 67 respectively, and closely adjacent its upper end in a bearing 68. 5 The lower end of the shaft 65 is provided with a shoulder 69 against which the worm 64 abuts and is held against said shoulder by a nut 70 threaded on the shaft 65 and secured in position by lock washers 71. The lower end of the shaft 10 65 extends below the lower bearing 67 and is provided with a thrust bearing comprising a washer or apertured disc 72 which is slotted to fit the flattened sides 73 of the shaft so that said washer is rotated with the shaft and is held thereon by 15 a castellated nut 74 secured by a cotter key 75. The upper surface of the washer 72 bears against a floating washer 76 which is slightly tapered in cross section toward the middle thereof, as shown clearly in Fig. 10, this construction aiding in the 20 lubrication of the bearing by permitting lubricant to be fed outwardly by centrifugal force. The floating washer 76 in turn bears on its upper side against a washer or apertured disc 77 which is secured to the housing by pins 78 so as to be constrained against rotation.

A cup shaped cover 79 is secured to the housing by cap screws 80 so as to provide a well or reservoir for lubricant in such manner that the shaft thrust bearing is substantially submerged 30 in lubricant at all times. An overflow opening 81 is provided so that lubricant may circulate through the bearing and overflow into the driving gear housing.

Lubricant is supplied to the drive gear shaft 35 and impeller shaft by an oil supply pipe 82, shown in Fig. 1, which conducts lubricant to the fitting 83, shown in Figs. 1 and 5 from which point it passes inwardly through a radially disposed opening 84 to an axially disposed bore 85 of attaching 40 bolt 86, the inner end of which is threaded into the housing. Lubricant passes inwardly from the passage 85 through a bore 87 in the housing to the lower bearing 67.

Axially extending grooves 88 are provided in the 45 lower half of this bearing for conducting lubricant downwardly to the thrust bearing at the lower end of the impeller shaft 65 and which comprises the discs 72, 76 and 77. The lower end of the impeller shaft 65 is provided with an axial bore 50 88, the lower end of which is closed by a plug 90. Radially extending bores 91 are provided at a point medially of the bearing 67 so that lubricant may pass from this bearing inwardly to the axial bore 88, thence upwardly to radial bores 92 which 55 are provided between the lower teeth of the worm and outwardly through radial bores 93 which are provided at the medial part of the bearing 66. The lower bearing 67 is also provided with a pipe or nozzle 94 which directs a stream of lubricant 60 directly into the teeth of the drive gear 48 as its teeth go into mesh with the worm 64.

The attaching bolt 86 is also provided with radially disposed bores 95 which permit lubricant to pass into a bore 96 formed in a cover plate 65 housing and which leads to the bearing 52, which bearing is peripherally grooved so that the lubricant passes completely around it. The shaft 44, at a point in registry with the peripheral groove in the bearing 52, is provided with a radially extending bore 97, the inner end of which communicates with an axially extending bore 98 which is drilled eccentrically in the shaft 44 and the outer end of which is closed by plug 99. At a point adjacent the plug 99 another radially extending 75

bore 100 is provided which permits the lubricant to pass from the bore 98 outwardly to the bearing surfaces of the removable bearing 50.

The fitting 83 is also provided with a lead pipe 101 which extends upwardly, as shown clearly in Fig. 5, and conducts lubricant through a suitable fitting 102 threaded in the upper part of the impeller shaft housing 25 to the upper bearing 68. The upper bearing 68 at its lower end is provided with a cylindrical skirt 103 which is in spaced relation to the impeller shaft 65 so that lubricant draining out of the bearing 68 and being thrown off of the shaft at its shoulder 104 is collected on the inner side of the skirt 103 and drains therefrom in relatively large drops.

It has been found in practice that due to the extremely high speed of rotation of the impeller shaft, lubricant draining out of the upper bearing is thrown off of the shoulder 104 in the form of a very fine mist having the appearance of blue smoke, which mist is readily drawn upwardly through the breather space provided around the shaft and opening in the top of the housing and is fed with the fuel into the motor. Lubricant draining from the skirt 103 drops downwardly in the space 105 which is provided in the housing 25 around the shaft 65 and passes through a drain hole 106 into the driving gear housing. All lubricant from the journaled parts thus drains into the driving gear housing 26 which serves as a reservoir for the lubricant and maintains a lubricant level therein which partially submerges the gear teeth on the lower part of the driving gear 48 so that these teeth are at all times lubricated when the motor is first started. After normal operation, lubricant is maintained in the housing 26 at the proper desired level by reason of the overflow openings 107 which are provided in registry with each other in the motor crankcase housing and supercharger driving gear housing, as shown more clearly in Fig. 4.

In practice, it has been found impossible and impracticable to effect a seal around the impeller shaft at the point where it passes into the impeller housing, and therefore means have been provided for effectively excluding lubricant of the bearing 68 from passing into the impeller housing and comprises an inverted saucer shaped oil slinger 102 tightly fitted on the shaft 65 between the upper bearing 68 and a shoulder 108, formed on the shaft, the peripheral edge of the oil slinger being curved downwardly and housed within an annular groove 110 formed in the upper end of the housing. The floor of the groove 110 progressively slopes downwardly so that oil passing therewith from the inner surface of the oil slinger is drained around the shaft and then downwardly through the breather opening 111, as shown more clearly in Fig. 4.

For convenience of manufacturing, the upper end of the housing is closed by a plate 112 which is secured to the housing by screws 113; said plate forming one wall of the impeller housing and being provided at its center with an opening through which the upper end of the impeller shaft 55 extends. The upwardly extending end 114 of the impeller shaft is frusto-conical in shape and provided at diametrically opposite sides with key ways 115 for receiving keys 116, said keys extending into rather loosely fitting slots 117 formed in the hub of an impeller 118. The impeller 118 is in the form of a disc having a lower plane side, and an upper side provided with radially disposed, axially extending fins or

blades 119 which are of decreasing height from the hub of the impeller outwardly.

The tapered end 118 of the shaft and the complementary hole formed in the impeller hub are disposed at a relatively steep angle so that tightening of the nut 120, by which the impeller is secured to the impeller shaft, will not exert an undue bursting strain on the impeller. However, the angle and fit of the impeller on the tapered shaft is such that when the nut 120 is securely tightened, the impeller is driven substantially entirely from its frictional fit on the shaft rather than through the keys 116, which keys are provided more as a safety precaution than as a regular driving means for the impeller.

When the supercharger is first assembled on the motor, a quantity of lubricant is introduced into the casing at 26 through an inspection plate 153 which is secured to the housing 26 by cap screws 156 so that the thrust bearing at the lower end of the impeller shaft and some of the teeth on drive gear 48 are submerged in oil, thus insuring lubrication of the driving gear teeth immediately upon starting of the motor. As the motor turns over and oil is driven through the motor lubricating system, lubricant under pressure will be supplied to the supercharger through the supply pipe 82 and thence into both bearings of the driving gear shaft as well as the three bearings of the impeller shaft. In addition thereto, as soon as the motor starts, a stream of oil will be projected out of the pipe 94 directly into the face of the teeth of the driving gear and worm as they come into engagement.

As shown in Fig. 7, the end of the driving gear shaft opposite to that connected to the accessory shaft is flattened as at 155 so as to be embraced between parallel fingers 156 of the armature shaft of a generator 157 which is secured to the housing 26 by cap screws 158.

Formal changes may be made in the specific embodiment of the invention described without departing from the spirit and substance of the broad invention, the scope of which is commensurate with the appended claims.

What is claimed is:

1. In a supercharger, a driving gear housing, a cover plate detachably secured to said housing, a drive shaft journaled in said housing and cover plate, a driving gear on said shaft, and a worm for meshing with said gear, the drive shaft bearing in said gear housing being removable and of sufficient wall thickness whereby said driving gear may be placed into and out of mesh with its worm by tilting or moving the drive shaft toward and away from said worm respectively when said bearing is removed and said cover plate is not secured to the housing.

2. In a supercharger construction, a housing having a removably mounted cover plate secured thereto and closing one wall thereof, a bearing bushing in said cover plate, a removably mounted bearing bushing in said housing axially aligned with the bearing bushing in said cover plate, a drive shaft journaled for rotation in said bearings, said drive shaft having a shoulder thereon adapted to engage the bearing bushing in said housing thus providing a thrust bearing for accurately positioning said drive shaft axially in said housing when said cover plate is secured in position, an area contact worm wheel secured on said shaft and a globoidal worm journaled for rotation in said housing adapted to mesh with said worm wheel.

3. In a supercharger construction, a housing

having a cover plate removably secured thereto and serving to close one wall thereof, a relatively thick wall bushing removably mounted in said housing, a bushing having a radially extending shoulder mounted in said cover plate and coaxially disposed with respect to the bushing in said housing, a drive shaft journalled for rotation in said bushings, said drive shaft having a shoulder thereon adapted to engage the shoulder of the bushing in said cover plate whereby to form a thrust bearing serving to position said drive shaft axially within said housing when said cover plate is secured thereto, an area contact worm wheel secured on said shaft and a globoidal worm journalled for rotation in said housing and adapted to mesh with said worm wheel.

4. In a supercharger, a driving gear housing, a cover plate detachably secured to said housing and serving to close one wall thereof, a relatively thick wall removable bushing mounted in the wall of said housing, a bearing bushing mounted in said cover plate and axially aligned with the bushing in said housing, a drive shaft journalled in said bushings, a thrust bearing on said drive shaft serving to retain the same in predetermined axial position with respect to said cover plate, an area contact worm wheel secured on said drive shaft and a globoidal worm mounted for rotation in said housing adapted to mesh with said worm wheel.

FLOYD F. KISHLINE. 15
